UNITED STATES PATENT OFFICE.

JOHN HOUP, OF SPRINGTOWN, PENNSYLVANIA.

FEED-PUMP FOR STEAM-BOILERS.

SPECIFICATION forming part of Letters Patent No. 254,321, dated February 28, 1882.

Application filed November 7, 1881. (No model.)

To all whom it may concern:

Be it known that I, JOHN HOUP, of Spring-
town, in the county of Bucks and State of
Pennsylvania, have invented a new and use-
ful Improvement in Hot-Water Feed-Pumps
for Steam-Boilers; and I do hereby declare
that the following is a full, clear, and exact
description of the same.

The object of my invention is to provide an
improved pump for supplying steam-boilers
with hot water at a higher temperature and
with greater uniformity of pressure than is
practicable with feed-pumps of ordinary con-
struction, thus economizing fuel and tending
to prevent the explosions due to the water be-
coming low therein by the defective working
of the hot-water feed-pumps, which is most
liable to occur when the water accidentally at-
tains a very high temperature in the heaters,
more especially the heaters of high-pressure
engines.

The invention is embodied in the construc-
tion and combination of parts, which I will
now proceed to describe, reference being made
to accompanying drawings, in which—

Figure 1 is a sectional elevation of the pump.
Figs. 2, 3, 4 are plan views of certain parts that
will be hereinafter referred to.

The vertical pump-cylinder A is provided
with a piston, B, reciprocated by piston-rod
C, attached to a crank-shaft or cross-head.
(Not shown.) Said piston B is annular in
form, and a relief-valve, b, is seated down-
ward therein; the same being guided in its
vertical movement by means of a pendent
stem, as shown.

In the upper portion of cylinder A is located
the outlet or discharge valve E, which seats
downward, and has a vertical guide-stem, d,
around which is coiled a spiral spring, f. The
function of the latter is to press down the valve
E promptly at the moment when the piston B
reaches the limit of its upward stroke.

A cock, G, is provided, for use in drawing
off the water from the cylinder when the pump
is not in operation. The letter H indicates
the hot-water-supply pipe, having a check-
valve, h, its location being thus intermediate
of the feed-pump, (whose parts have been above
described,) and the feed-water heater (not
shown) or other source of supply. Between
such heater and valve h, I place an auxiliary

force-pump, whose cylinder S is a continuation
of the said tube H. The piston T is recipro-
cated simultaneously with the piston B, and 55
in the same direction. At the bottom of the
cylinder S is a check-valve, u. A tube, P,
having gage-cock p, connects this auxiliary
pump S T u with the heater or source of sup-
ply, (not shown,) which is in practice located 60
above the level of the pump-cylinder A, so
that the pump will always be primed and sup-
plied by gravitation of the feed-water itself,
independent of the pressure of the atmosphere.

Figs. 2, 3, 4 are plan views respectively of 65
the guide i for discharge-valve E, the seat k
for said valve, and the lower part, l, of the pis-
ton B. Since both pistons B T reciprocate to-
gether and in the same direction, the piston
B forces a charge of hot water and steam, &c., 70
past the outlet-valve E at one end of the cyl-
inder A. The piston T of the auxiliary feed-
pump S at the same time forces the next
charge of hot water past check-valve h in pipe
H into the other end of the cylinder A, thus 75
affording good and uniform charges or sup-
plies of hot water to the pump-cylinder A.
At the limit of its upward movement the pis-
ton B comes in close contact with the seat of
valve E, and before the piston begins its re-
verse movement the said valve E closes, and 80
hence as the piston continues to recede a par-
tial vacuum is for an instant formed between
it and the discharge-valve seat, which aids in
overcoming the inertia of the relief-valve b of 85
said piston, so that water and steam pass up-
ward and fill such vacuum-space more quickly
than would be otherwise possible. The vac-
uum therefore aids in raising water and steam
above the piston B, and relieves the pump of 90
labor to that extent. The artificial pulsation
thus produced relieves any undue back-press-
ure that may arise from the formation of steam
in the pump-cylinder and supply-pipes, owing
to the high temperature attained by the sur- 95
rounding materials. It is hence practicable
to supply a steam-boiler with water of higher
temperature than by means of the ordinary
feed-pump, since there is greatly less danger
of explosion from the rapid formation of steam 100
in the cylinder and supply-pipes.

What I claim is—

1. In a pump for feeding hot water to steam-
boilers, the combination of the cylinder A, pis-

ton B, the latter having the relief-valve *b*, the spring check-valve *h* in the supply-pipe, and the outlet-valve in the discharge end of said cylinder, all arranged to operate as shown and described.

2. In a pump for feeding hot water to steam-boilers, the combination, with cylinder A, piston B *b*, and outlet and check valves, of the auxiliary feed-pump consisting of cylinder S,

valved piston T, and valve *u*, all as shown and described, to operate, as hereinbefore specified, to produce an artificial pulsation, and relieve undue pressure in the cylinder and supply-pipes.

JOHN HOUPT.
